can Bosch Corporation, Springfield, Mass., a
corporation of New York

Application February 12, 1935, Serial No. 6,192

12 Claims. (Cl. 123—149)

This invention relates to magnetos and more particularly to magnetos as employed in the ignition systems of internal combustion engines having differing numbers of cylinders. In the past, a different magneto was required for each engine of differing numbers of cylinders as one, four or six. In accordance with this invention a single, standard magneto may be employed and individual adaptors used to conform to the cylinder complement of different engines.

An object of this invention is to provide a magneto which has a broader field of application.

Another object is to provide a magneto which is more economical in production.

Still another object is to provide a magneto which may readily be adapted to different engine requirements by changing the distributor unit thereon.

Still a further object is to provide a magneto in which the distributor gear is of improved and simplified construction.

Other objects and advantages will in part be specifically stated and in part be obvious when the following specification is read in connection with the drawing, in which:

Fig. 1 is a side elevation showing in section the magneto and removable distributor plate; Fig. 2 is an end view of the magneto, showing the distributor plate; and Fig. 3 is an alternative construction, showing a different type of removable distributor plate and a different kind of distributor gear.

In the description of the alternative forms of construction, like numerals will indicate like elements.

Referring in more detail to Fig. 1, the numeral 1 indicates a rotor shaft, journaled in bearings 2 and 3, which are carried respectively by a die cast housing 4 and a bracket 5 supported in the housing. A magnet rotor 6 is suitably mounted upon the shaft 1 in operative relation to pole-shoes formed on vertical stator laminations, not shown in detail and forming no part of the present invention. A laminated cross member 7 is mounted on the upper ends of the vertical laminations and carries the usual primary and secondary windings, indicated generally as 8, which overlie the rotor 6. The high tension terminal 9 of the windings 8 is connected by the rigid conductor 10 with a contact button 11 which is centrally mounted on the distributor gear 12. While the distributor may be either a brush or jump spark type, the latter type is shown in Fig. 1 and operates as follows: A stud 13 is mounted on the gear 12 and is electrically connected with the

spring mounted contact button 11. The high tension current is thus led to the stud 13 and jumps the small clearance gaps to the outlet terminals 14, shown in Figs. 1 and 2 as inserts in the distributor plate 15. The distributor gear 12 is mounted on a stub shaft 16 which is journaled in a suitable bearing step 17 formed in the distributor plate 15 and located centrally with respect to the output terminal 14. A metallic bushing 17a may be inserted in the molded bearing step 17 in 10 order to provide a wear-resisting bearing surface, and the bearing end of the stub shaft may be hollowed to receive a suitable lubricating grease which reaches the bearing surfaces through two small radial holes.

The rotor shaft 1 has a cam surface 18 formed adjacent one end thereof, which may operate any suitable breaker lever, not shown. Fixedly mounted on the end of shaft 1 adjacent the cam surface is a pinion 19 in driving relation with the distributor 12. The gear 12 is formed of fabric laminations impregnated with one of the artificial resins or phenolic condensation products and in itself comprises an insulating support for the high tension lead, thus dispensing with the usual construction of a gear driving a separate distributor rotor which carries the high tension lead.

While a distributor for a four cylinder engine is shown in Fig. 1, the magneto may quickly be adapted to engines having a differing number of cylinders by removing the distributor plate 15 and replacing it with one having the proper number of outlet terminals. Preferably, different sizes of pinions are used for the various distributor 35 gearing ratios required by the respective engines, the gear 12 being left unchanged in size but mounted on a center appropriate for the pinion. To secure proper adjustment, the gear and pinion must mesh in predetermined relationship 40 and a tooth of each is marked to indicate the meshing position desired. In order to more readily determine that they are properly meshed, an observation window 20 is formed in the distributor plate 15.

Fig. 3 shows another form of the distributor gear 12 and plate 15. In this instance, the gear 12 is molded with the high tension conductor as an insert. The teeth of gear 12 are molded at the same time and are made of sufficient width 50 and strength to avoid chipping. In this form, the pinion 19 is journaled at 21 in the distributor plate 15, in addition to the gear 12. A loose driving connection is made with the end of the rotor shaft 1, which allows the pinion 19 55

to be removed with the distributor plate assembly. Thus, in both embodiments, a unitary distributor assembly is provided which may be quickly removed and replaced by another assembly suitable for a different engine. A suitable distributor may readily be designed to meet the requirement of any engine having two or more cylinders, while for one cylinder engines no rotary distributor is needed. In the latter instance the sparking impulses are taken directly from the secondary of coil 8. A very flexible and economical magneto unit is furnished which is reliable in operation and simple in construction.

10 It will be apparent that many changes and 15 modifications may be made by anyone skilled in the art without departing from the spirit and scope of the invention expressed in the following claims.

We claim:

20 1. In a magneto, a distributor plate, outlet terminals on said plate, a gear journaled on said plate and being entirely supported thereby, and means including said gear for supplying said terminals with current impulses.

25 2. In a magneto, a distributor plate, outlet terminals formed on said plate, a gear journaled on said plate and being entirely supported thereby, and a high tension lead carried by said gear and cooperating with said outlet terminal.

30 3. In a magneto, a distributor plate of molded insulation material, outlet terminals on said plate, a bearing step formed in said plate, a gear journaled in said bearing step and being entirely supported thereby, and a high tension lead carried 35 by said gear and cooperating with said outlet terminals.

40 4. In a magneto, a distributor plate of molded insulation material, outlet terminals on said plate, a bearing step formed in said plate, a gear of insulating material journaled in said bearing step and being entirely supported thereby, and a high tension lead carried by said gear and cooperating with said outlet terminals.

45 5. In a magneto, a distributor plate of molded insulation material, outlet terminals on said plate, a bearing step formed in said plate, a bushing positioned in said bearing step, a stub shaft journaled in said bushing, a gear fixed on said stub shaft and entirely supported thereby, and a high tension lead carried by said gear and cooperating 50 with said outlet terminals.

5. In a magneto, a distributor plate, outlet

terminals on said plate, a distributor gear journaled in said plate, a pinion journaled in said plate in driving relation to said gear, a driving connection between said pinion and the rotor shaft of said magneto, and a high tension lead carried by said gear and cooperating with said outlet terminals.

5

7. In a magneto, a molded insulation distributor plate, outlet terminals on said plate, a bearing step in said plate being centrally located with respect to said terminals, a gear journaled in said bearing step and being entirely supported thereby, and a high tension lead carried by said gear and cooperating with said outlet terminals.

10

8. In a magneto having a rotor, a distributor plate, outlet terminals on said plate, a distributor gear journaled on said plate and being entirely supported thereby, means including said gear for supplying said terminals with current impulses, and a pinion fixedly mounted on said rotor and 20 meshed with said gear.

15

9. In a magneto, a distributor plate, outlet terminals on said plate, a bearing in said plate, a shaft rotatably mounted in said bearing and having one end projecting therefrom, and a distributor gear secured to said projecting shaft end whereby said bearing and shaft comprise the 25 principal supporting means for said gear.

25

10. In a magneto, a distributor plate, outlet terminals on said plate, a distributor gear carrying a high tension lead in cooperative relation to said terminals, supporting means for said gear including a bearing in said plate and a shaft journaled in said bearing, whereby said plate and said gear are removable as a unitary structure.

30

11. In a magneto, a distributor plate, outlet terminals on said plate, a distributor gear carrying a high tension lead in cooperative relation to said terminals, supporting means for said gear including a bearing in said plate and a shaft journaled in said bearing, and resilient means for 40 maintaining said shaft seated in said bearing.

40

12. In a magneto, a distributor plate, outlet terminals on said plate, a distributor gear carrying a high tension lead in cooperative relation to said terminals, supporting means for said gear including a bearing in said plate and a shaft journaled in said bearing, and resilient means comprising a high tension lead for maintaining said shaft seated in said bearing.
